ARC LAMP

Alfred Rüttenauer, Berlin-Charlottenburg, and
Otto Fritze, Berlin, Germany, assignors to General
Electric Company, a corporation of New
York

Application January 26, 1932, Serial No. 589,004
In Germany February 23, 1931

3 Claims. (Cl. 176—1)

Our invention relates to arc lamps of the type which comprises highly refractory electrodes having a filament mounted in multiple therewith sealed in a light transmitting enclosure containing 5 an inert gas or vapor. More particularly our invention relates to means for supporting said filament. The filament in such a lamp is provided for the purpose of facilitating the formation of an arc between the electrodes by ionizing 10 the gas therebetween due to the emission of electrons from said filament. With the present methods of mounting the filament, the arc first appears across the filament terminals due to the fact that the filament is at that time at a higher 15 temperature than the electrodes. This results in disintegration of the filament at the starting points of the arc with a consequential decrease in the life thereof. This disadvantage is obviated according to our invention by mounting the filament 20 loosely on the inner leading-in wires instead of rigidly as at present, thereby setting up a high resistance at those points which will allow the passage of current therethrough at the comparatively high starting voltage but will considerably 25 impede the flow of current when the voltage drops and the arc appears, so that said arc will appear initially across the electrodes. Other features and advantages of our invention will appear from the following detailed description 30 of species thereof.

In the drawing, Fig. 1 is an elevation of a lamp comprising our invention; and Figs. 2 and 3 are detailed views in perspective of modifications of the filament connections.

35 Referring to Fig. 1, the lamp comprises a bulb 10 and base 11. For the purpose of transmitting ultra-violet radiations, said bulb 10, containing argon, nitrogen, or other inert gases or vapors, may be made of quartz glass or of a borosilicate 40 glass free from lead and iron. The lamp also comprises a stem tube 12, an exhaust tube 13, outer lead wires 14, conductors 15 connected thereto and sealed into a stem press 16, and inner lead wires 17 connected to said conductors 15. 45 Support wires 18 mounted on inner lead wires 17 carry electrodes 19 of a highly refractory metal such as tungsten. The support wires are provided with loops 20 which support loosely the ends of a filament 21 hanging therefrom. Said filament 21 is further supported by a loop 22 at the end of a wire 23, the other end of which is held by an insulating disk 24 which is in turn held up by support wires 25 mounted on the inner 50 lead wires 17. In order to obtain a substantial amount of ultra-violet radiation it is preferred to include a small quantity of mercury 26 so that mercury vapor will be formed and its radiation will be added to the light.

Referring to Fig. 2, a filament 27 comprises a single loop passing through the loops 20 of the support wires 18 and hanging loosely therefrom. Said filament 27 is further supported, to hold it open in the form of a loop in different positions 5 of the lamp, by loops 28 at the ends of wires 29 which are in turn supported by a disk 30 similar to disk 24 in Fig. 1.

Referring to Fig. 3, support wires 31 mounted on inner lead-in wires 17 are flattened at portions 10 32 in which holes are provided for the reception of pins 33 comprising heads 34 which seat loosely on the portions 32. A filament 35 is clamped or welded at each end to the ends of pins 33 and is additionally supported in a loop 36 at the end 15 of a wire 37 similar to the wire 23 in Fig. 1.

What we claim as new and desire to secure by Letters Patent of the United States, is:

1. In an electric lamp, the combination of a pair of separated electrodes, a filament in multiple with the gap between said electrodes and means for supporting said filament and having a loose connection therewith comprising lead wires having holes therethrough and headed pins passing through said holes and united to said filament.

2. In an electric discharge lamp, the combination of a bulb, a pair of inner leads in said bulb for carrying current, an electrode secured to each of said leads, and a filament connected in multiple with the gap between said electrodes and supported by said inner leads, the connection between filament and leads being of sufficiently high resistance to allow the passage of current through said filament at the comparatively high 35 starting voltage of the lamp but considerably impeding the flow of current when the arc appears and the voltage drops so that the said arc appears initially across the electrodes.

3. In an electric discharge lamp, the combination of a bulb, a pair of inner leads in said bulb for carrying current, an electrode secured to each of said leads, and a filament connected in multiple with the gap between said electrodes and supported by said inner leads and having a loose 40 connection therewith, the area of contact between said filament and leads being comparatively small so as to produce a high resistance, the connection between said filament and leads being of sufficiently high resistance to allow the passage 45 of current through said filament at the comparatively high starting voltage of the lamp but considerably impeding the flow of current when the arc appears and the voltage drops so that the said arc appears initially across the 50 electrodes.

ALFRED RÜTTENAUER.
OTTO FRITZE.
